CLAIM

The ornamental design for a wireless lighting control system device, substantially as shown and described.

DESCRIPTION

FIG. 1 is a top perspective view of an embodiment of the new design;

FIG. 2 is a bottom perspective view of the embodiment of FIG. 1;

FIG. 3 is a top view of the embodiment of FIG. 1;

FIG. 4 is a bottom view of the embodiment of FIG. 1;

FIG. 5 is a left side view of the embodiment of FIG. 1;

FIG. 6 is a right side view of the embodiment of FIG. 1;

FIG. 7 is a front view of the embodiment of FIG. 1; and,

FIG. 8 is a rear view of the embodiment of FIG. 1.

The broken lines shown in the drawings are for the purpose of illustrating portions of the article that form no part of the claimed design.
